(57) **CLAIM**

The ornamental design for an electrical meter bracket as shown and described.

DESCRIPTION

FIG. 1 is a top front side perspective view of an electrical meter bracket showing my new design;
 FIG. 2 is a top view of the electrical meter bracket;
 FIG. 3 is a front view of the electrical meter bracket;
 FIG. 4 is a bottom view of the electrical meter bracket;
 FIG. 5 is a rear view of the electrical meter bracket;
 FIG. 6 is a left side view of the electrical meter bracket; and,
 FIG. 7 is a right side view of the electrical meter bracket.
